(57) **CLAIM**

The ornamental design for a vehicle, as shown and described.

DESCRIPTION

FIG. 1 is a perspective view of the vehicle of the present design;

FIG. 2 is a top plan view thereof;

FIG. 3 is a bottom plan view thereof;

FIG. 4 is a right side elevational view thereof, the left side elevational view being identical thereto; and,

FIG. 5 is a front elevational view thereof, the rear elevational view being identical thereto.

The broken lines shown in the drawings depict portions of the vehicle that form no part of the claimed design.

1 Claim, 5 Drawing Sheets

FIG. 2

FIG. 3

FIG. 5
